[57] **CLAIM**

The ornamental design for a chair, as shown and described.

DESCRIPTION

FIG. 1 is a right hand elevation of the chair according to the invention, the reverse side being the mirror image thereof; and

FIG. 2 is a front view of FIG. 1;

FIG. 3 is a rear view of FIG. 1; and

FIG. 4 is a top plan view of FIG. 1.

The dot-dash lines used to show a base member are for illustrative purposes only.

Fig. 2

Fig. 1

FIG. 4

FIG. 3
